UNITED STATES PATENT OFFICE.

ALONZO E. RHOADES, OF HOPEDALE, MASSACHUSETTS, ASSIGNEE TO DRAPER CORPORATION, OF HOPEDALE, MASSACHUSETTS, A CORPORATION OF MAINE.

SPINNING OR TWISTING FRAME.

Application filed April 7, 1924. Serial No. 704,557.

To all whom it may concern:

Be it known that I, ALONZO E. RHOADES, a citizen of the United States, and resident of Hopedale, county of Worcester, State of Massachusetts, have invented an Improvement in Spinning or Twisting Frames, of which the following description, in connection with the accompanying drawing, is a specification, like characters on the drawing 10 representing like parts.

This invention relates to ring spinning or twisting frames or similar machines in which the yarn being wound onto the yarn carrier or bobbin runs from a traveller eye. 15 In starting the winding of the yarn, the yarn frequently breaks because of the sudden strain placed upon it and this is especially true of very fine yarns. This is due to the comparatively long run of yarn extending from the traveller eye to the barrel of the 20 yarn carrier which is subjected to the starting strain.

The object of the present invention is to provide means for adjusting the traverse 25 motion mechanism so that when the winding operation is started the yarn extending from the traveller eye to the barrel of the yarn carrier will contact with the base of the yarn carrier which usually comes closely adjacent the traveller eye. This frictional engagement of the yarn with the base of the 30 yarn carrier has the effect of substantially limiting the starting strain to the lead or run of yarn between the traveller eye and the periphery of the base which is a very 35 short distance. Immediately after the machine is in operation and the yarn has started running through the traveller eye and is being wound upon the barrel of the 40 yarn carrier the traverse motion mechanism is restored to normal condition and the operation proceeds as usual.

The object of the invention is further to provide a simple and efficient mechanism 45 for adjusting the traverse motion mechanism to secure these results.

These and other objects and features of the invention will appear more fully from the specification and accompanying drawings and will be particularly pointed out in 50 the claims.

In the drawings:

Fig. 1 is a front elevation of a portion of a ring twister showing a preferred form of

the invention and with the traverse motion 55 mechanism adjusted for starting;

Fig. 2 is a detail view similar to Fig. 1 showing the mechanism in normal position;

Fig. 3 is a view in transverse section taken on the line 3—3 of Fig. 2 and looking in the direction of the arrows;

Fig. 4 is a detail to show the position of the yarn in starting with this invention.

The invention is applicable to various types of ring spinning, ring twisting and similar machines and for convenience of illustration is here shown in connection with a twister. As the invention relates solely to one feature of the machine it is only necessary to describe and illustrate those parts 70 of the machine directly concerned with the present invention.

The frame of the machine comprises suitable uprights 1, the right-hand one only of which is shown, between which extend the 75 usual spindle rail 2 and arch rail 3. The spindles 4 are mounted for vertical rotation in the spindle rail 2 and are shown as driven by the whirls 5 in the usual manner. Each spindle carries a suitable yarn carrier. In 80 the case of the twister these yarn carriers are of spool shape having the barrels 6, heads 7 and bases 8. It will be noted that the bases 8 are of much larger diameter than the barrels and while these bases are 85 herein shown as upright cylinders they may be of various shapes.

The usual ring rail 9 is supported upon lifter rods, one of which is shown at 10. These lifter rods are mounted for vertical 90 movement or reciprocation in suitable bearings in the spindle rail 2 and arch rail 3. Rings 11 are supported on the ring rail concentric with the spindles and each ring 95 guides the usual traveller 12 through which the yarn is led onto the yarn carrier.

The operation of such a machine is a familiar one. As the lifter rods 10 are reciprocated the ring rail is moved up and down and the yarn running from the traveller eyes to the yarn carriers is thus traversed the length of the barrels 6 of the yarn carriers so as to be wound evenly thereupon.

The reciprocating movement of the lifter rods and ring rail is effected from a traverse 105 motion mechanism which may be of any desired pattern. Such a mechanism usually includes a unitary quadrant 13 and rocker arm

14 mounted on a transverse pivot 15. The rocker arm carries a roll 16 upon which rests a step 17 secured to the bottom of the lifter rod 10. A flexible connector such as a chain 18 extends over and is connected to the quadrant at one end and to suitable mechanism at the other end by which the chain is moved backward and forward. As the chain is pulled the lifter rods and ring rail rise and as the chain is let out the lifter rods and ring rail descend. But in the normal operation of such a mechanism the ring rail does not descend sufficiently to allow the base of the yarn carrier to project above the top of the rings or the planes of the traveller eyes. Otherwise the yarn would be wound on the bottom of the barrels of the yarn carriers.

In this invention means are provided for manually adjusting the traverse motion mechanism so that when the frame is put into operation the ring rail will be lowered sufficiently to cause the bases of the yarn carriers or bobbins to stand well above the top of the rings or the level of the eyes of the travellers, all as shown in Fig. 1 and in detail in Fig. 4.

In the construction illustrated as embodying a simple and preferred form of the invention the quadrant and rocker arm are mounted on a square section shaft 19 having cylindrical end sections 15 mounted in bearings in a hanger 20 secured to the bottom of the arch rail 3. As shown, the quadrant is a separate piece from the rocker arm but is rigidly secured thereto by a bolt 21. The quadrant piece is provided with a rigid arm 22 extended downwardly, and in the lower end of this arm is secured a stud 23 on which is pivotally mounted the hub 24 of an anchor arm 25. This anchor arm extends up in line with the quadrant 13 and to it is secured the end of the chain 18. As illustrated, the chain is provided at its end with a hook 26 and this hook is secured to the anchor arm 25 by passing therethrough and being held in place by the nut 27.

An eccentric 28 is rotatably mounted in the quadrant in line with the anchor arm 25. This eccentric is provided with a polygonal shank 29 by means of which it may be rotarily adjusted as by the use of a socket wrench. The eccentric also is provided with a projection 30 normally contacting with a stop lug 31 on the quadrant.

The operation of the construction will now be clear. When the mechanism is running under ordinary conditions the projection 30 of the eccentric abuts the lug 31 and the eccentric is projected against the anchor arm 25, as shown in Fig. 2. Under these conditions the traverse of the ring rail will not carry the bases of the yarn carriers above the level of the traveller eyes. When, however, the mechanism is to be started either after doffing or in starting for any other reason

the operator places a wrench on the shank 29 of the eccentric and adjusts the eccentric by giving it a turn of about 180° , or to a position such as shown in Fig. 1. This allows the unitary quadrant and rocker arm 14 to swing to the right without changing the position of the anchor arm 25, and consequently allows the lifter rods and ring rail to descend slightly. The lifter rod is so arranged that this descent of the ring rail causes the bases of the yarn carriers to project above the level of the traveller eyes, or bring them to a position such as shown in Figs. 1 and 4. Consequently the lead or run of yarn 32 extending from the traveller eye 12 on its way to the barrel 6 of the yarn carrier will be brought into frictional engagement with the base of the yarn carrier. Thus the strain upon the yarn is reduced and takes place through the comparatively short section of yarn extending from the point of contact on the base of the yarn carrier to the traveller eye. As soon as the yarn has begun to wind upon the yarn carrier and the machine is in full operation, the operator reverses the position of the eccentric, or brings it to its normal position and the spinning, twisting or other operation proceeds as usual.

Having thus described the invention, what is claimed as new and desired to be secured by Letters Patents is:

1. A ring spinning or twisting frame comprising a plurality of vertical rotated spindles, yarn carriers having bases of greater diameter than their barrels mounted on the spindles, a vertical reciprocable ring rail supporting rings concentric with the spindles, travellers on the rings, a traverse motion mechanism for effecting the reciprocation of the ring rail, and means for adjusting the traverse motion mechanism to allow the ring rail to stand at the lower limit of its traverse with the eyes of the travellers below the level of the top of the yarn carrier bases whereby in starting the yarn may be led from the travellers into engagement with the bases before being wound on the barrels, thus to minimize the starting strain upon the yarn.

2. A ring spinning or twisting frame comprising a plurality of vertical rotated spindles, yarn carriers having bases of greater diameter than their barrels mounted on the spindles, a vertical reciprocable ring rail supporting rings concentric with the spindles, travellers on the rings, a vertically movable lifter rod for the lifter rail, a traverse motion mechanism including a rocker arm for effecting the movement of the lifter rod, a traverse reciprocating connector, an anchor member mounted on the rocker arm and secured to the connector, and means for adjusting the anchor member relatively to the rocker arm to allow the ring rail to stand

at the lower limit of its traverse with the eyes of the travellers below the level of the top of the yarn carrier bases whereby in starting the yarn may be led from the travellers into engagement with the bases before being wound on the barrels, thus to minimize the starting strain upon the yarn.

3. A ring spinning or twisting frame comprising a plurality of vertical rotated spindles, yarn carriers having bases of greater diameter than their barrels mounted on the spindles, a vertical reciprocable ring rail supporting rings concentric with the spindles, travellers on the rings, a vertically movable lifter rod for the lifter rail, a traverse motion mechanism including a pivotally mounted unitary quadrant and rocker arm, an eccentric mounted and rotatably adjustable in the quadrant, an anchor arm pivoted on the rocker arm and engaging the eccentric, a traverse chain extending over the quadrant and secured to the anchor arm, and means for rotatably adjusting the eccentric thus to adjust the position of the anchor arm relatively to the rocker arm to allow the ring rail to stand at the lower limit of its

traverse with the eyes of the travellers below the level of the top of the yarn carrier bases whereby in starting the yarn may be led from the travellers into engagement with the bases before being wound on the barrels, thus to minimize the starting strain upon the yarn.

4. A ring spinning or twisting frame comprising a plurality of vertical rotated spindles, yarn carriers having bases of greater diameter than their barrels mounted on the spindles, a vertical reciprocable ring rail supporting rings concentric with the spindles, travellers on the rings, a traverse motion mechanism for effecting the reciprocation of the ring rail, and means for adjusting the traverse motion mechanism to lower the ring rail upon starting so that the bases of the yarn carriers shall project above the traveller eyes and thus cause the yarn running from the travellers to engage the bases of the yarn carriers at the start.

In testimony whereof, I have signed my name to this specification.

ALONZO E. RHOADES.
